UNITED STATES PATENT OFFICE.

EUSTACE HENRY TENNYSON D'EYN COURT AND FREDERICK SKEENS, OF WHITEHALL,
LONDON, ENGLAND.

GUN MOUNTING.

Original application filed June 7, 1918, Serial No. 238,661. Divided and this application filed May 7, 1921. Serial No. 487,698.

(GRANTED UNDER THE PROVISIONS OF THE ACT OF MARCH 3, 1921, 41 STAT. L. 1313.)

To all whom it may concern:

Be it known that we, EUSTACE HENRY TENNYSON D'EYN COURT and FREDERICK SKEENS, both subjects of the King of Great Britain, residing at the Admiralty, Whitehall, in the county of London, England, have invented certain new and useful Improvements in Gun Mountings (for which we have filed application in Great Britain, No. 10 18,421, dated Dec. 22, 1916, Patent No. 121,746), of which the following is a specification.

This invention consists in an improved combined gun mounting and protective shield which, while capable of being employed on any movable or stationary structure, is particularly applicable to armoured or armed cars, such as for example as those employed in overcoming heavy defence work 20 used in trench warfare.

It has heretofore been proposed to mount a gun in a sphere which is pivoted in a step bearing to rotate about a vertical axis, and which can roll on a suitable track about a 25 horizontal axis, the sphere being arranged to move within an aperture in a fixed shield; also a gun has been trunnioned in a part spherical mounting which is arranged to rotate either about a horizontal or a vertical axis in an opening in a fixed shield, the mounting being provided with an elongated aperture through which the barrel of the gun protrudes and which allows movement of the gun for training or elevating as the 30 case may be, the mounting towards the rear being shaped so that it fits closely around the gun barrel during its movement relatively to the mounting; also it has been proposed to form or fit to a gun a ball capable of 35 movement within a socket secured to the wall of the structure within which the gun is placed, the ball having a through opening for a sighting telescope.

A combined gun mounting and protective 40 shield according to this invention is characterized by a spherically shaped shield disposed in an aperture in the structure carrying the gun and formed with a sighting aperture and with a gun aperture closely 45 embracing the gun, a forked member, means

for pivoting the gun to said member for elevating and means for pivoting said member to the structure for training.

In the accompanying drawings which illustrate a construction embodying this invention, Figure 1 is an elevation, Figure 2 is an elevation looking in the direction of the arrow in Figure 1, Figure 3 is a plan and Figure 4 a part sectional elevation of a form of shutter suitable for the construction 55 of mounting.

In the drawings 1 is the plating or bulk-head of the vehicle or stationary structure and 2 is a plate attached to the part 1. The parts 1 and 2 are formed with holes in 65 which the shield 13 (hereinafter described) is disposed. In the construction shown virtual trunnions are provided for the gun, which is arranged to slide into and out of position in the mounting. The gun 4 is supported in a clamping ring 11 having a clamping band 11' readily removable such as by withdrawal of one or both securing pins 11² according as to whether the band is pivoted or completely removable. The 70 clamping ring is carried by a bracket 12 secured to a spherically shaped shield 13 mounted within a gun port or other enveloping aperture formed in the structure carrying the gun, and the ring or bracket is 75 provided with trunnions 14 engaging in bearings in a fork 15 mounted to rotate about a vertical axis by means of a stud 15' engaging in a step or other bearing secured to the structure such as directly or indirectly to the plates 1 or 2. The trunnions are retained in position in the bearing by hinged or pivoted caps 15² secured in position by wing bolts 16. The shield 13 is shown in slightly exceeding the hemisphere, 80 and is provided with a sighting aperture 17. It will thus be seen that when the gun is in position, the gun and the shield can be moved in a universal manner about the horizontal trunnion axis and about the vertical 85 axis of the forked pivot, the line of sight through the aperture being always fixed relatively to the longitudinal axis of the gun.

By removing the clamping band 11' the 100

gun can be withdrawn and by removing the wing bolts 16 and turning back the caps 15² the shield can be removed.

In order to close the opening in the shield 5 when the gun is removed a shutter in the form shown in Figure 4 is provided which consists of a spherically shaped portion 18 of sufficient area to cover the whole of the aperture in the shield and is carried by a 10 tubular or other shaped member 18' provided with a shouldered recess 18² or the like over which the clamping band 11' can be placed to secure the shutter in position, so that the shutter and shield move about the 15 same centre.

Combined mountings and shields with shutters as above described provide for an armoured or armed vehicle or other movable or stationary structure being fitted with a 20 large number of gun positions without the necessity of having a gun mounted permanently in each, as the guns may be dismounted from one position and remounted either in another position in the structure 25 or outside the structure if desired such as when engaged in land warfare, thereby enabling a minimum number of guns to be carried and their most effective use obtained, without leaving openings in the structure 30 through which the personnel inside would be exposed to counter attack, the openings being closed by securing the shutters as above described after removal of the guns.

We would here state that the expression 35 spherically shaped member used in the ensuing claiming clauses is intended to include a member of spherical or partly spherical shape.

What we claim and desire to secure by 40 Letters Patent of the United States is:—

1. In a gun mounting, the combination with the gun and the structure carrying it, of a spherically shaped shield disposed in an aperture in said structure and formed 45 with a sighting aperture and with a gun aperture closely embracing the gun, a forked member, a bracket on said shield for supporting the gun, means for pivoting said bracket to said forked member for elevating, 50 and means for pivoting said member to the structure for training.

2. In a gun mounting, the combination with the gun and the structure carrying it, of a spherically shaped shield disposed in an

aperture in said structure and formed with 55 a sighting aperture and with a gun aperture closely embracing the gun, a forked member, a bracket on said shield for supporting the gun, means for detachably connecting the gun to said bracket, means for pivoting said bracket to said member for elevating and means for pivoting said member to the structure for training.

3. In a gun mounting, the combination with the gun and the structure carrying it, of 60 a spherically shaped shield disposed in an aperture in said structure and formed with a sighting aperture and with a gun aperture closely embracing the gun, a member carrying a clamping band for detachably connecting the gun to the shield so that the latter and the gun move together, a forked member, horizontal trunnions connecting the first mentioned member to said forked member, and a vertical training pivot connecting 75 said forked member to the structure.

4. In a gun mounting, the combination with the gun and the structure carrying it, of a spherically shaped shield disposed in an aperture in said structure and formed 80 with a sighting aperture and with a gun aperture closely embracing the gun, a forked member, a bracket on said shield for supporting the gun, means for pivoting said bracket to said member for elevating, means 85 for pivoting said member to the structure for training, and a shutter for closing the gun aperture in said shield when the gun has been removed, said shutter being adapted to be held in place by said bracket.

5. In a gun mounting, the combination with the gun and the structure carrying it, of a spherically shaped shield disposed in an aperture in said structure and formed with a sighting aperture and with a gun aperture 95 closely embracing the gun, a member carrying a clamping band for detachably connecting the gun to the shield so that the latter and the gun move together, a forked member, horizontal trunnions connecting the first 100 mentioned member to said forked member, a vertical training pivot connecting said forked member to the structure and a shutter held in position by said clamping band for closing the gun aperture in said shield when 105 the gun has been removed.

EUSTACE HENRY TENNYSON D'EYN COURT.
FREDERICK SKEENS.
